ELECTRICAL SYSTEM FOR PROLONGING
LIFE OF COATED CATHODES

Clarence W. Hansell, Port Jefferson, N. Y., assignor to Radio Corporation of America, a corporation of Delaware

Application September 24, 1948, Serial No. 51,035

5 Claims. (Cl. 250—27)

1

The present invention relates to a means for prolonging the life of electron discharge devices and more particularly to an arrangement of electrodes in association with potential sources for preventing appreciable evaporation of the emissive coating on coated cathodes employed in such devices and subjected to conditions of operation requiring the cathode to be instantaneously emissive but calling only for an intermittent current output therefrom.

Some electron discharge devices employ the Wehnelt or oxide type of cathode which comprises a layer of mixed barium and strontium oxides held on a metal surface. High electron emission density is obtained at moderately high temperatures because the oxide in an activated Wehnelt cathode does not have chemically balanced or stoichiometric proportions of oxygen and metal but has an excess of barium in the oxide. The excess barium converts the oxide into a semi-conductor of a type which emits electrons, when heated, relatively easily, and perhaps causes to appear on the surface a thin bound layer of barium which also emits electrons relatively easily. However, under certain conditions this emission density does not remain constant but is subject to large variations depending upon the manner in which the electron emission is utilized. For example, it has been found that the activation or electron emission of a cathode tends to diminish quickly following maximum activation and then gradually when the cathode is kept hot and no emission current is drawn from it. Thus, in applications of electron discharge devices to uses in radio telegraph transmitters, pulse communication systems, electrical computers, and even in continuously operating A. C. oscillators and amplifiers where the operating frequency is relatively low, the intermittent character of the operation causes a reduction in the activation of the cathode.

This reduction in the electron emission density and phenomena accompanying loss of barium from the cathode, in intermittent operations has heretofore discouraged the use of tubes of the coated cathode type in high voltage, high power applications where intermittent use is involved, such as for transmitting purposes, and has limited the use of this type of cathode to low voltage, low power tubes ordinarily employed in radio receivers, or in relatively low power transmitters.

It is therefore a principal object of the invention to provide an improved electron discharge device having a coated cathode subjected to such

2

operating conditions that it will stand up well under conditions of use involving high voltage and high power.

A further principal object is to provide an improved electron discharge device having a coated cathode that will have a relatively long life although current is drawn therefrom only intermittently.

Another principal object is to provide operating conditions for the cathode such that it may be operated at higher temperatures and higher electron emission densities without reduction in its life expectancy.

Another object is to preserve the emission characteristics of a coated cathode under intermittent conditions of use.

An additional object is to prolong the life of electron discharge devices having coated cathodes, subjected to intermittent operation involving standby periods with the cathode maintained at a high temperature.

Another object is to provide a system permitting a coated cathode type of electron discharge device to be employed advantageously in pulse emission work at relatively high voltages, high current densities and high powers.

Another object is to make it possible to operate oxide coated cathodes at larger electron emission densities.

Another object is to provide a system for operating a coated cathode at electron emission temperatures without deterioration in its activation during intermittent standby periods.

Another object is to provide a system for prolonging the life of an electron discharge device having a coated cathode, under conditions of use involving high voltage and high power and periodic interruptions in the drawing of useful current therefrom.

A further object is to provide a system for preventing the evaporation of the coating material from coated cathodes during conditions of use in which the cathode is maintained at an electron emitting temperature and the voltage difference between the cathode and anode is periodically decayed to substantially zero.

Another object is to prevent the evaporation of emissive materials from a hot coated cathode during intermittent periods of decay of the electrostatic field between the cathode and an associated anode.

A still further object is to provide a system for ionizing the particles of emissive material leaving the coating of a hot coated cathode during intermittent periods when the potential differ-

ence between the cathode and an associated anode is not sufficient to produce an ionizing electron flow therebetween.

Another object is to provide an electrostatic field adjacent the surface of a coated cathode during intermittent periods when the cathode is at an emitting temperature, but no normal useful current is drawn therefrom for ionizing particles of emitting material leaving the cathode to cause such particles to return to the cathode.

High mercury vapor pressure very greatly reduces the rate of diffusion of barium molecules away from the cathode, while electron current is not flowing, so that they cannot move far in a given time, and also increases the probability that the barium molecules will be ionized and returned to the cathode when electron current is flowing. Increased ionization of barium vapor, due to the presence of mercury vapor, is attributed to lengthening of electron paths in the electrical discharge by non-ionizing encounters of electrons with mercury vapor molecules.

Where great care has been taken to prevent operation at lower vapor pressures, and various other precautions have been taken, it has been observed that glass envelopes of mercury vapor rectifiers have remained almost free of cathode coating material.

On the other hand maintaining high mercury vapor pressures tends to reduce the permissible operating voltages by lowering the dielectric strength of the vapor.

It is therefore another important object of the invention to provide a discharge device having an indirectly heated cathode and operable at relatively low vapor pressure and at relatively high voltages.

Further objects and advantages of the invention will become clear as the description proceeds.

Referring to the drawing:

Figure 1 shows in sectional elevation an evacuated electron discharge device incorporating the invention;

Figure 2 shows a circuit arrangement employed in association with the electron discharge device of Figure 1 to form a system for providing a long life device under intermittent operation; and

Figure 3 shows an elevation partly in section of a mercury rectifier incorporating the invention.

A Wehnelt or oxide cathode comprises a metal supporting base, commonly of nickel or metal alloy, over which has been applied a thin layer consisting of a finely divided mixture of the oxides of strontium and barium. The oxide coating, so long as it is made of relatively pure oxides, is a poor electron emitter. It is made into a good emitter by giving it an excess of barium. One method to obtain an initial moderate excess of barium is to raise the oxide to a relatively very high temperature while the vacuum tube containing the cathode is still connected with a vacuum pump. The high temperature breaks down a little of the barium oxide into barium and oxygen. The oxygen escapes faster than the barium and is removed by the vacuum pump as a gas, leaving an excess of barium in the cathode coating.

An alternative process of initial activation omits raising the cathode temperature far above the normal operating temperature and instead uses a temporary gas discharge between the cathode and other electrodes so as to force an electrical current through the oxide coating. This also gives an initial activation by breaking down

some of the oxide electrolytically and allowing oxygen to escape, leaving an excess of barium.

Initial activation is sometimes obtained by using a base metal of such a nature that it will react with the oxide to some extent to remove oxygen, leaving an excess of barium.

If, after the initial activation, electron emission current is drawn from the cathode and the emission current density at the cathode is increased to a high enough value by applying sufficient potential between the cathode and other electrodes, it is found that an additional or final activation takes place with temporary or transient release of more oxygen, accompanied by an increase in electron emission. Sometimes this final activating step is performed while the tube is on the pump and the released oxygen is pumped out, after which the tube is sealed off.

If now a finished tube has its cathode heated, but no electron emission current drawn from it, it will be found that barium evaporates from the cathode which is deposited on other tube elements, including the outer envelope. The rate of evaporation is not constant but starts at a maximum rate which then diminishes with time toward nearly zero, or a very low value. The loss of barium due to evaporation lowers the cathode activation and diminishes the available electron emission.

Suppose now, after the activation has diminished, that potentials are applied to the other electrodes and electron emission current is drawn from the cathode. It then is found again that oxygen is evolved transiently which leaves in the cathode an added excess of barium to more or less balance what has been lost due to barium evaporation.

The transient evolution of oxygen has been attributed to electrolytic separation of barium and oxygen due to electrical current flowing through the oxide coating. The accumulation of excess barium, as the electrolytic separation proceeds, lowers the volume resistivity of the oxide and electron conduction through the oxide then shunts or short circuits the electrolytic path sufficiently to stop or very greatly reduce the electrolytic conduction. It therefore tends to stop evolution of oxygen with passage of time.

It will be noted that maintaining either zero emission current, or nearly emission limited current, continuously soon results in a steady state condition such that neither oxygen nor barium continues to be lost from the cathode in substantial amounts. On the other hand a change from one condition to the other is followed by loss of a quantity of either barium or oxygen. Thus, when the rate at which the electron emission current is started and stopped is not too rapid, the life of the cathode can be measured by the number of times the electron emission current is started and stopped.

The oxygen and barium lost alternately from the cathode recombine on other internal tube surfaces and often are apparent as a dark deposit built up on the inside of glass tube envelopes. Tubes which finally fail in a normal manner, due to inadequate cathode emission, often have been found to have lost practically all the barium oxide from the cathode coating.

Drawing out a continuous electron emission current from the cathodes, especially if the current is made so large as to be nearly emission limited, tends to stop all loss of cathode material and to provide a great increase in tube life. At the same time the other electrodes, particularly the control

electrodes, can be kept relatively clean and un-activated so as to have low secondary electron emission. The secondary emission is a common cause of operating difficulty and premature failures, especially in tubes of the larger sizes, operated at high voltages.

Likewise, if no materials such as oxygen and barium escape from the cathode, ions are not formed far enough from the cathode to cause destructive ion bombardment of the cathode.

It should be observed that intermittent current can be drawn from the cathode without loss of coating material if the frequency of applying or interrupting the current is high enough so that molecules cannot move any substantial distance from the cathode after interruption of the current before the current flows again. A very rough estimate is that frequencies much above about one megacycle per second, are sufficient to keep the cathode protected in high vacuum tubes. In gas-filled tubes the lowest permissible frequency depends largely upon the gas density and pressure. In the case of mercury vapor rectifiers, the cathodes may be protected down to operating frequencies below 60 cycles, but only if great care is taken never to operate the rectifiers unless the mercury vapor pressure is relatively high, corresponding to operating temperatures above the minimum specified by most manufacturers in the United States.

Referring now in more detail to the drawing, there is shown in Figure 1 an evacuated electron discharge device capable of operation at a relatively high potential and power level in a chain of amplifiers in a radio telegraph transmitter, in which the current in the device is keyed on and off with the signals. This is one kind of use in which ordinary oxide cathode tubes have failed in the past.

The device comprises an envelope formed of a plurality of tubular members 10, 11, 12, 13, 14, 15 and 16 and containing an electrode assembly including an indirectly heated cathode 17, energized by heater 18, an anode 19, a screen grid 20 and a control grid 21. Cooling fins 22 are provided for the anode.

According to the invention, there is provided between the cathode 17 and control grid 21, an additional grid 23. The function of this last-named grid is to draw current from the cathode during the intervals when operation of the device requires no anode current. To enable grid 23 to perform this function, it is connected to a suitable source of voltage that is positive with respect to the cathode.

Figure 2 shows a circuit in which the device illustrated in Figure 1 may be used. It comprises an electron tube having an oxide cathode 17, cathode heater 18, anode 19, and grids 20, 21 and 23 interposed in succession between the anode and cathode. It is provided with tuned frequency input and output circuits and appropriately placed radio frequency by-passed condensers. The tube and circuits shown provide a screen grid amplifier to which an extra grid has been added adjacent the cathode and to which circuit components including a direct current voltage source positive with respect to the cathode, a resistance, an inductance and a condenser by-passed to ground have also been added, to permit carrying out the present invention. The electron discharge device and the circuit here shown operate in a manner similar to a class "C" radio frequency amplifier at a radio frequency assumed to be above one megacycle. The cathode heater 18 is supplied with heater current from a direct

current power source which may have a pressure of 50 volts to give the cathode 17 an initial temperature high enough to provide electron emission. The grid 23 is connected to a source of positive direct potential which may have a voltage of plus 50 volts. This voltage is sufficient to draw substantial electron emission current from the cathode when no direct or average anode current is flowing. When anode current does flow the current flow to grid 23 will diminish and may reach zero or even reverse if the grid itself has thermionic or secondary emission. During the flow of anode current the effect of the grid 23 upon the anode current and upon cathode emission and life may be negligible. However, during intermittent periods when no anode current is flowing, the effect of grid 23 is to continue the drawing of electrons from the cathode.

Preferably, though not necessarily, the grid 23 and the heater 18 are supplied from the same source of power, which as shown, is a +50 volts source. Thus, by means of a suitable resistance arrangement in the power connections, the heater current may be caused to vary to keep a nearly constant cathode temperature, even though the electron current to grid 23 and the consequent heating of this grid should vary over a large range in response to telegraph keying.

Thus, when the telegraph key or relay controlling the transmitter is open with consequent absence of radio frequency power in the circuits and a zero anode current due to a negative control grid bias potential, the arrangement of Figure 2 provides for a combination of cathode heater power and of power dissipation at grid 23 due to electron emission current resulting in a desirable operating temperature. At the same time this arrangement will prevent or reduce the loss of cathode material through evaporation due to the continuous flow of electrons from the cathode to the grid 23.

In addition, when the telegraph key is closed to cause radio frequency power to appear in the amplifier circuit and D. C. current to flow from the anode, the arrangement according to the invention is also advantageous. In this situation the direct anode current will be made up of electrons which are pulled through grid 23 during periods of positive or less negative direct potential on the control grid 21. The average current to grid 23 will therefore be diminished. As a result, the direct potential of this grid as well as the heating current, normally tend to rise to a higher value while the telegraph key is closed. This rise in direct potential of grid 23 and cathode heating current however, is preferably adjusted in accordance with the invention by adjustment of resistance values and power source potentials, so that there is substantially no tendency for the cathode temperature to change due to intermittent operation of the amplifier. To this effect the movable arm 44 is adjustable to any desired position with respect to resistor 45 shown in Figure 2. Therefore, according to this aspect of the invention the electron emission can be held at all times at an optimum value, even though the operation is intermittent or the radio frequency power levels may change.

Since the grid 23 is required to dissipate considerable power, while no anode current is flowing, it may be raised to a relatively high temperature and may itself emit electrons. This generally does no harm so far as operation of the tube is concerned since emission from the grid 23 simply adds to the total emission available to

supply the anode current. In some cases, in order to draw enough electron emission to protect the cathode while no anode current is flowing, the heating of grid 23 might become excessive unless special cooling means are provided. In very large tubes and in tubes operated with large electron current densities cooling of the grid by means of circulating cooling fluid may be employed as is sometimes done in tubes now in use. In other cases the grid 23 may be made with strips or sheets of metal set in radial planes with respect to the axis of the tube, to provide for more effective cooling.

It is well to note also that the impedance and resistance between grid 23 and cathode 17 should be kept low enough so that reversed grid currents can not result in excessive potentials on grid 23.

Advantages similar to those secured in telegraph operations referred to above will also be secured when the invention is used in applications characterized by continuous operation, as in some industrial heating applications where the frequency at which the amplifier shown in Figures 1 and 2 operates, is of a relatively low value, for example, from 10 to 100 kilocycles per second. At such frequencies, even when the operation is continuous, the time periods between pulses of anode current will be long enough to permit escape of barium from oxide cathodes of ordinary tubes. However, if the type of tube and circuit of the invention shown in Figures 1 and 2 are employed, and the electron emission current is kept high enough while no anode current is flowing, there will be substantially no escape of cathode material. In this application also, therefore, the invention makes it possible to utilize oxide cathodes where they have never been used successfully before.

An additional important advantage of the invention is that it makes possible the operation of oxide cathodes at higher temperatures and therefore at higher electron emission densities than heretofore possible, due to continuous inhibition of loss of cathode material. There is thus obtainable, according to the invention, greater useful electron currents per unit of power used to heat the cathode. In addition, it permits a broadening of the frequency band of amplifiers such as may be employed for example in television broadcasting transmitters, by increasing the ratio of electron current to dielectric capacity current in the tube and circuits.

A further advantage of the invention is that it makes possible a wider choice of materials for activating the cathode. It permits use of more effective activators than barium, such as sodium, potassium, rubidium and caesium. These better activators are too volatile to stay on and in the cathode coatings for any substantial time while large density electron currents are not flowing, and in which electron emission current cannot be drawn out at all times. However, when sufficient electron current is constantly drawn out as provided for by the invention, these better activators can be used.

While the foregoing description concerns an embodiment of the invention in an evacuated space discharge device, the invention may also be used advantageously in gas discharge tubes, such as a mercury vapor rectifier shown in Figure 3. This tube comprises an envelope 24 within which is disposed an electrode assembly comprising a cathode 25, heater 26, a keep-alive electrode 27, a shielding electrode 28 and anode 29.

The device illustrated in this figure is provided with a pool of mercury 30.

The cathode 25 is a unipotential electrode equipped with vanes 31 to increase its surface area. The surface area including the vanes is coated with barium and strontium oxides in the usual manner.

The keep-alive electrode 27 and shielding electrode 28 comprise a double walled electrode, serving the double function of keep-alive electrode and of a cathode heat shield and heater. Openings 32, 33 in the double walls of the electrodes 27, 28 permit electron current to be drawn out in a gaseous discharge to the anode 29. It will be noted that the arrangement of the anode 29 and disc support 34 of the electrode 28 is such that all possible paths through which barium vapor might escape to the relatively cool glass envelope for condensation thereon, are baffled.

The cathode 25 is connected to a source of low voltage D. C. current 35 by leads 36, 37 in series with resistor 38. The cathode heater 26 is also connected to the direct current source 35 by a lead 39 and an adjustable portion of resistor 40. The keep-alive electrode 27 is connected to the heater lead 39 by lead 41 and adjustable resistor 42. The shielding electrode 28 is connected to cathode lead 36. The current to be rectified is fed to the cathode 25 by way of lead 36 and resistor 38. The rectified output is taken from the anode connection 43 at the top of the device.

In operation of the tube shown in Figure 3, the cathode 25 is provided with initial heating energy by passing an electrical current of suitable value through the cathode heater 26. When electron emission from the cathode 25 is available due to its temperature, current at low potential is drawn to the keep-alive electrode 27. This results in additional heating of the cathode as a consequence of current flow between the cathode and the keep-alive electrode. However, in accordance with the circuit shown in Figure 3, the resistance 42 automatically serves as a compensating means by causing a drop in heater current with a consequent reduction in its heater power. Therefore, at all times when the cathode is hot, relatively large electron emission current is drawn from it to virtually stop barium evaporation even in the absence of anode current.

While, as shown, the keep-alive electrode is sufficiently positive with respect to the cathode, during periods when no anode current is drawn from the device, to draw cathode current and thus prevent evaporation of the cathode material, when anode current is drawn from the device the keep-alive electrode loses its energization in accordance with the invention so that it does not use up electron emission but leaves it available to supply the anode current. This is due to the voltage drop across resistance 38 which makes the cathode potential more positive with respect to the keep-alive electrode and reduces the amount of electron current flowing to the keep-alive electrode.

It will therefore be seen that the invention broadly concerns a novel tube structure having an electrode performing a novel function, and a novel circuit organization making possible the novel function referred to. Furthermore, the invention is helpful in connection with either evacuated or gas discharge devices including gas discharge tubes with other gases than mercury vapor. It permits use of oxide coated cathodes in applications and under conditions in which such cathodes have heretofore been regarded as unusable.

By preventing loss of cathode activating material the life expectancy of the cathodes is very greatly increased while, at the same time, internal arcing, instability due to secondary emission and high velocity ion bombardment of the cathode are all eliminated or greatly reduced.

Many departures may be made from the specific embodiments described without going beyond the spirit and scope of the invention as pointed out in the appended claims. For example, means to maintain electron emission current between anode current pulses may be applied to pulsed magnetrons and other types of oscillators used in radar and pulse type communications equipment and in almost all other kinds of thermionic devices utilizing thermionic emission intermittently.

What I claim is:

1. In an electronic system including an electron discharge device having an oxide coated cathode, means for preventing evaporation of the cathode coating, said means comprising a system for drawing emission current from said cathode during active and inactive periods of said device, said system including a grid adjacent said cathode and a direct current voltage supply more positive than said cathode connected to said grid; and a system for maintaining the temperature of the cathode constant during said active and inactive periods, said last named system comprising a heater for said cathode and a connection between said heater and said grid, said connection including a resistance element for predetermined ohmic value for adjusting the power supply to said heater to a lower magnitude during said inactive periods than during said active periods, said grid drawing emission current during said inactive periods and being heated thereby, said cathode being heated by radiation from said grid and by said lower magnitude power supply to the temperature assumed thereby during said active periods.

2. In combination, an electron discharge device adapted for pulsed operation at a frequency below one-half megacycle, and having an oxide coated cathode and an anode energized by relatively high direct current voltage; means for continuously drawing emission current from said cathode during and between the pulses of said pulsed operation for at least partially preventing evaporation of the cathode coating, said means including an electrode adjacent said cathode, a voltage source, and a connection between said electrode and said voltage source; and means for maintaining the temperature of said cathode constant during and between said pulses, for further at least partially preventing evaporation of said cathode coating, said last named means including a heater for said cathode, and a resistance in said electrode-to-voltage-source connection, said heater being connected to an intermediate portion of said resistance, whereby said electrode dissipates more power and radiates more heat to said cathode during intervals between said pulses than during said pulses, for maintaining the temperature of said cathode during said intervals at the temperature assumed thereof during said pulses.

3. In combination, an electron discharge device adapted for operation at a frequency of less than one-half megacycle and including a cathode having an oxide coating thereon for electron emis-

sion and an anode for receiving said emission in pulses at said frequency; means for maintaining the temperature of said cathode constant during a period including a plurality of said cycles, said means including a voltage source, an electrode adjacent said cathode, a connection between said electrode and said voltage source, said connection including a resistance element of predetermined value, a heater for said cathode, said electrode receiving the emission from said cathode during intervals between said pulses and being heated thereby, whereby said cathode is heated both by said heater and by heat radiated to it by said electrode, to a predetermined temperature, said last named connection being adjustable for increased energization of said heater during said pulses and during reduced current flow in said electrode, whereby said cathode is heated to said predetermined temperature during said pulses.

4. In an electronic system including an electron discharge device having a cathode provided with an oxide coating; means for preventing evaporation of said coating, said means including an auxiliary electrode adjacent said cathode; a heater for said cathode; a circuit arrangement including said electrode, said heater and a source of positive voltage for maintaining the temperature of said cathode constant during pulsed operation below radio frequency of said system; and a circuit arrangement including said electrode, said positive voltage source, an inductance between said source and said electrode and a condenser by-passed to ground between said inductance and said electrode, for drawing emission current from said cathode during operation of said system at a radio frequency below one-half megacycle and between the pulses of said frequency.

5. A system for protecting a coated cathode from coating evaporation comprising means for maintaining said cathode at a desired constant operating temperature during pulsed emissions therefrom at a frequency below one-half megacycle, and for collecting emission from said cathode during intervals when no useful emission is required, said means including a grid adjacent said cathode, a heater for said cathode, a connection between said heater and grid, a voltage source positive with respect to said cathode connected to said grid, and a resistance in said connection of predetermined ohmic value for heating said cathode to a desired operating temperature that remains constant during said pulsed emissions and during the intervals therebetween.
